ELECTRIC-DISCHARGE DEVICE

Edward A. Colson, Hillsboro County, N.H., assignor to Edgerton Germeshausen & Grier Inc., Boston, Mass., a corporation of Massachusetts

Filed Sept. 29, 1958, Ser. No. 763,982

3 Claims. (Cl. 313—198)

The present invention relates to electric-discharge devices and, more particularly, to flash tubes of the type that are triggered to produce flashes of illumination for such purposes as stroboscopy or flash photography and the like.

Flash tubes generally employ a glass, fused quartz, or similar light-transparent envelope containing a gaseous medium within which an electrical discharge may pass to produce a flash of illumination. The environment within which the flash tube is to be operated determines, in many cases, the material from which the flash-tube envelope is manufactured. As is disclosed, for example, in United States Letters Patent No. 2,277,698, issued on March 31, 1942, to Kenneth J. Germeshausen, the operator may sometimes have to be protected from possible fracture of the flash lamp by enclosing the same in an outer glass or other housing. If a flash lamp, moreover, is to be operated in liquids, it must also be protected from its environment, as discussed, for example, in co-pending application, Serial No. 437,647, filed June 18, 1954, by Harold E. Edgerton, for Underwater Flash-Producing System, now Patent No. 2,872,622.

The present invention is primarily directed to the problem of providing satisfactory electric-discharge devices, including flash tubes and the like, that may operate under more adverse environmental conditions, such as in a potentially explosive atmosphere or at extreme altitudes where prior-art flashlamps have been found to be unsuitable.

A further object is to provide a novel flashtube and the like that may be of extremely small dimensions, as well.

Other and further objects will be explained hereinafter, and will be more particularly pointed out in connection with the appended claims.

In summary, from perhaps its broadest aspect, the invention contemplates an electric-discharge device having a discharge chamber provided with electrodes between which a discharge may pass in the chamber and electrode lead connections extending external to the chamber, the chamber and at least the portions of the externally-extending electrode lead connections adjacent thereto being imbedded within a block of electrically insulative light-transparent material. Preferred details are herein-after set forth.

The invention will now be described in connection with the accompanying drawing, the single figure of which illustrates the invention in preferred form connected with a preferred electronic circuit for operating the same, though other types of circuits may also be employed.

Referring to the drawing, a flash tube is shown comprising a preferably, though not essentially, tubular glass or other light-transmitting envelope 1, the space within which defines a gas-discharge chamber 3 filled with any desired gas, such as xenon gas, as employed, for example, in the type FX-4 flashtube, manufactured by Edgerton, Germeshausen & Grier, Inc. The principal electrodes within the gaseous chamber 3 defined by the envelope 1

2

are shown in the form of a pair of rod-like electrodes 5 and 7, spaced at opposite ends of the flashtube envelope 1 and extending through seals at the end walls thereof, as at 9 and 11, respectively. This construction may, as an

illustration, be of the type described in United States Letters Patent No. 2,756,361, issued to the said Kenneth J. Germeshausen, on July 24, 1956; or in copending application, Serial No. 588,906 of the said Harold E. Edgerton, filed June 1, 1956, for Flash Tube and Apparatus.

10 The electrodes 5 and 7 are shown preferably disposed substantially along the axis of the tubular envelope 1 and are provided with lead extensions 9' and 11' adjacent but external to the envelope 1. A preferably externally disposed trigger electrode 13, comprising one or more turns of wire, may also be employed to assist in the initiation of the electrical discharge within the gaseous chamber 3 between the principal electrodes 5 and 7 in well-known manner, as described in the said United States Letters Patent and applications.

15 As an illustration, in the case of the said FX-4 flashtube, a capacitor C may be charged from a direct-current voltage source, +, —, through a charging resistor or other impedance R₁, supplying energy for producing the main flash discharge between the principal electrodes 5 and 7 to which it is connected. The voltage stored upon the capacitor C, however, is not of itself sufficient to

20 produce the before-mentioned electrical discharge through the gaseous medium 3 until a trigger voltage is applied between, for example, the trigger electrode 13 and the cathode principal electrode 7, as by means of the secondary winding S of a trigger transformer T. The trigger impulse for energizing the trigger transformer T may be produced by closing a switch S, thereby to discharge a trigger capacitor C' that has normally become charged

25 from the positive potential source terminal + through a charging resistor or other impedance R₂ and the primary winding P of the trigger transformer T. The closure of the switch S causes the capacitor C' to discharge its voltage through the primary winding P, producing a trigger pulse that is conveyed to the secondary winding S and thence to the trigger electrode 13, thereby to initiate the discharge of the main flash capacitor C between the principal electrodes 5 and 7. Other types of flash-producing circuits may, of course, be employed, as discussed in the said Letters Patent and applications.

30 When a flash tube is subjected to the before-mentioned unusual environmental conditions, it is generally found to be too fragile or otherwise unsatisfactory. As an illustration, flashtubes of this character require a relatively high starting voltage. This is no particular problem under ordinary laboratory or other operating conditions. This does become a serious problem, however, if the tube 1 must be operated in an explosive atmosphere, or at extreme altitudes, or under other unusual conditions.

35 Flashtubes, as another example, may also be required to take photographs within a gas well, or within the human stomach for diagnostic purposes, or in some other equally unusual environmental condition. The tube, moreover, may be subjected to extreme mechanical shock and vibration, as in connection with its use in modern aircraft and the like.

40 It has been discovered, however, that a particular treatment of the tube 1 will enable it to be used in all such unusual environmental circumstances. That treatment involves the encapsulating or imbedding of the flashtube 1 within a block of light-transparent mechanically rugged material such as, for example, a light-transmitting epoxy-type plastic resin. The tube 1 is accordingly shown imbedded within a preferably substantially cylindrical block 15 of such a light-transparent material. By embedding the complete flashtube 1, the external relatively fragile trigger electrode 13, the relatively fragile elec-

trode extensions 9' and 11' constituting part of the electrode-lead connections that pass through the end seals 9 and 11 of the tube 1, and at least a portion of the further lead connections 9", 11" and 13' associated with the flashtube 1, all within the block 15, the effects of mechanical shock or heavy vibration, the danger of explosion, the effects of extreme temperature variations and other undesirable environmental conditions are completely overcome.

In the particular illustrated construction, the further lead connections 9", 11" and 13' are shown carried substantially parallel to the axis of the tube 1, though to the side thereof, through the preferably substantially cylindrical external block 15 to a common lower end thereof. They are there connected with insulation-covered terminal lead connections 2, 4 and 6, the insulation of which is preferably of a material, such as vinyl insulation, that may be well bonded to the material employed for the block 15.

It has been found that the before-mentioned epoxy resin, provides insulation of the glass tube structure 1 against severe thermal shock. The tube 1, thus encapsulated was operated from a temperature environment of -55° centigrade to up to $+95^{\circ}$ centigrade, repeatedly, and without causing any mechanical damage. Such a tube has also been operated successfully when immersed in water and other liquids, and even to photograph the inside of a gas well where explosion was of extreme concern. Such flashtubes have also been successfully operated within the block 15 in high-flying aircraft at altitudes of up to 70,000 feet, for the purpose of producing flash records of moving dials or meters and the like, and was found well to withstand the shock and vibration requirements produced by such operation.

It will also be observed that the block 15 may obviously be dimensioned such that it does not appreciably increase the space occupied by the flashtube 1. Extremely small light sources that must be subjected to extreme environmental conditions may thus be provided. The FX-4 flashtube 1, before-mentioned, thus embodied an epoxy-type resin block 15, for example, and operated at a rate of one flash per second with an energy input of about $\frac{1}{8}$ of a watt-second will normally operate with a minimum life of 4,000 light flashes. If greater life is required, of course, less energy per flash and a lower repetition rate may be employed. If, moreover, the block 15 is formed so as to have its own internal chamber 1 as a cavity therein, with appropriate electrodes 5, 7, etc., the effects of such environmental conditions may also be mitigated against, though it is preferred, for purposes of manufacture, and because flash lamps have other uses in other environmental conditions, to employ the separate flashtube envelope 1, as described; it being understood, however, that the term "chamber," as used herein, is intended to embrace both such types of construction.

Further modifications will occur to those skilled in the art and all such are considered to fall within the spirit and scope of the invention, as defined in the appended claims.

What is claimed is:

1. A gaseous-discharge device having a flashtube comprising a light-transparent envelope defining a gas-filled discharge chamber provided with a pair of spaced principal electrodes between which a discharge may pass in the chamber, electrode extensions extending from said principal electrodes, respectively, through seals in said envelope and externally of said envelope, and electrode-lead connections extending from said principal electrode extensions externally of the envelope, the envelope, the electrode extensions, and at least the portions of the electrode-lead connections near the envelope being embedded within a block of electrically insulative light-transparent material, said electrode extensions being supported solely by said envelope seals and by the material of said block.

2. The device of claim 1, further comprising an auxiliary trigger electrode external to the envelope for initiating the discharge, and electrode-lead connections extending from said trigger electrode, the trigger electrode and its lead connections being embedded within said block of material.

3. The gaseous-discharge device of claim 2, said envelope being tubular and said block being substantially cylindrical, said principal electrodes extending substantially along the axis of said envelope, said lead connections extending in part along the length of said envelope within said block material and terminating at one end of said block in insulation covered terminal lead connections, the insulation material being bonded to the block material.
